INVENTOR

RICHARD LIST

BY *Thomas D. Donnelly*
ATTORNEY

UNITED STATES PATENT OFFICE.

RICHARD LIST, OF DETROIT, MICHIGAN.

SASH LOCK.

Application filed October 23, 1925. Serial No. 64,340.

My invention relates to a new and useful improvement in a sash lock and has for its object the provision of a sash lock adapted for use with window sashes slidably mounted in frames, which will be simple in structure, economical of manufacture and highly efficient in use.

Another object of the invention is the provision of a sash lock of this class, which is provided with a retractable locking finger and having pivotally mounted positively operated means for retracting the finger to inoperative position.

Another object of the invention is the provision in a sash lock of this class, comprising a minimum number of parts, and so arranged and constructed as to simplify the mounting of the lock on the frame with which used.

Other objects will appear hereinafter.

The invention consists in the combination and arrangement of parts hereinafter described and claimed.

The invention will be best understood from a reference to the accompanying drawings, which form a part of this specification and in which,

Fig. 1 is a side elevational view of the invention, mounted on a window sash, showing parts in section,

Fig. 2 is a sectional view taken on substantially line 2—2 of Fig. 1,

Fig. 3 is a rear elevational view of the locking mechanism used in the invention,

Fig. 4 is an elevational view of the sash in fragment prepared for mounting the locking mechanism thereon.

As shown in the drawings, the invention is adapted for use with a window sash 9, slidably mounted in a window frame 10. Mounted on the face of the windowframe 10 which faces the sash 9 is a bar 11, having a plurality of shoulders 12 formed thereon. In mounting the device on the sash 9, the sash 9 is first provided with a circular recess 13, which is formed by drilling, with the conventional size of window used in railway carriages and the like, a hole one and one quarter inch in diameter and one

quarter of an inch deep. Formed in the window sash is a passage 14, which is drilled transversely thereof and communicates with the hole 13, and also, with an enlarged recess 15 formed in the face of the window sash. Mounted in the recess 15 is a circular guide 16 having a bore 17 formed

therein, said bore being preferably square. Projecting outwardly from the guide 16, at opposite sides, are wings 18 and 19, which are secured to the sash 9 by screws or other suitable means. A lock plate 20 is provided and secured by screws 21, or other suitable means, to one face of the sash 9, a flange 22 extending at right angles to the plate 20 and engaging one edge of the rail of the window sash 9. Projecting outwardly from the inner face of the plate 20 is a stud 23, upon which is pivotally mounted an operating arm 24, having the angularly turned portion 25, the arrangement comprising a bell crank with an elongated operating arm. Pivotally connected at one end to the end of the arm 25, is a bolt 26, which engages in the passage 14 and projects through the recess 15 and beyond the face of the sash 9, when in operative position, the portion 27 projecting through the guide 16 being square in cross section and reduced in size from the remainder. Mounted on a stud 29, projecting from the inner face of the plate 20 is a spring 28, which is adapted for rocking the arm 25 into position for projecting the reduced portion 27 of the bolt into engagement with one of the shoulders 12. Projecting outwardly from the plate 20 is a stationary raising arm 30.

In operation, when it is desired to raise the window, the arm 24 is brought into closer relation to the frame 30, as shown in dotted lines in Fig. 1, so as to retract the portion 27 of the bolt within the guide 16. When the window is raised or lowered to the desired position, a release of the arm 24 will permit the spring 28 to effect the outward movement of the bolt to engage the shoulders 12.

In mounting the device, the recess 13 is formed as well as the passage 14, and the bolt 26 slid into the passage 14, the arm 25 engaging in the recess 13. It is, therefore, believed evident that the mounting of the device upon a window sash is a simple operation, easy of performance with the labor reduced to a minimum.

While I have illustrated and described the preferred form of structure, I do not wish to limit myself to the precise form of structure shown, but desire to avail myself of such variations and modifications as come within the scope of the appended claim.

Having thus described my invention, what I claim as new and desire to secure by Letters Patent is:

A sash lock of the class described, adapted for mounting on a window sash, slidably mounted in a window frame and comprising: a lock plate; a flange on said plate, at one end thereof, extending at right angles thereto, said plate being adapted for mounting on one face of a rail of said window sash and said flange engaging another face of said rail, said rail having a recess formed in said face communicating with a passage extending in the direction of said frame, said passage terminating in an enlarged recess, adjacent said frame; a stud projecting outwardly from the inner face of said lock plate; a bell crank pivotally mounted on said stud, having an elongated arm projecting outwardly through a slot formed in said flange; a lock bolt slidably

mounted in said passage and pivotally connected to the inner end of said bell crank, said lock bolt projecting through said enlarged recess and adapted, when in operative position, for extending beyond the surface of said sash rail; a shoulder bearing plate mounted on said frame for engaging said lock bolt; an additional stud projecting from the inner face of said lock plate; a spring mounted on said additional stud for normally retaining said lock bolt in operative position; a guide member mounted in said enlarged recess having a bore formed therein for the reception of said lock bolt, said lock bolt being reduced adjacent one end for projecting through said bore.

In testimony whereof, I have signed the foregoing.
